UNITED STATES PATENT OFFICE.

CHARLES H. LUCAS, OF CANTON, MAINE, ASSIGNOR OF ONE-HALF TO
WALTER W. CHAFFIN, OF SAME PLACE.

DEVICE FOR FITTING HAIR-SPRINGS TO WATCHES.

SPECIFICATION forming part of Letters Patent No. 278,347, dated May 29, 1883.

Application filed January 27, 1883. (No model.)

To all whom it may concern:

Be it known that I, CHARLES H. LUCAS, of Canton, in the county of Oxford and State of Maine, have invented certain new and useful 5 Improvements in Devices for Fitting Hair-Springs to Watches; and I do hereby declare that the following is a full, clear, and exact description of the invention, which will enable others skilled in the art to which it appertains 10 to make and use the same, reference being had to the accompanying drawings, and to letters of reference marked thereon, which form a part of this specification.

Figure 1 is a side elevation. Fig. 2 is a top 15 plan. Fig. 3 is a sectional view of the bed-plate recess and mirror. Fig. 4 is a view of the vertical center, with its jaw to grasp the spring. Fig. 5 is a top view of the same in part section. Fig. 6 shows a vertical section 20 of the concave point of the vertical center. Fig. 7 is a top view of the device for holding the regulator-pins. Fig. 8 is a side view of same.

Same letters show like parts.

25 My invention relates to machines for putting hair-springs into watches and chronometers.

It consists, first, in the combination of a socket on the bed-plate, an upright rod, a horizontal slide-rod, certain jaws, a vertical center, a clamp, a bed-plate, and a mirror, as hereinafter described; second, of a vertical center, *p*, having one end pointed and the other concave, as herein set forth; third, in the combination of a vertical center, *p*, block, sliding rod, pins, and set-screw, as hereinafter described; fourth, in combination with the vertical rod *j*, a horizontal rod, a socket, set-screw, and a bristle, arranged and operating as hereinafter described.

40 In the accompanying drawings, *a* shows the bed-plate of my machine. *b* shows the movable jaws. *c* is a recess in the bed-plate, into which is set the mirror *d*. The jaws *b* are set upon posts *e*, which are held in position by the nuts *f* on the under side of the bed-plate. The jaws *b* can be turned around in horizontal planes on the posts *e*. These jaws *b* are operated by thumb-screws *g* in closing. They can be operated by springs, if desired. They are 45 to hold the movement of the watch while the hair-spring is adjusted, as will be hereinafter

described. The bed-plate is circular, and is supported by legs *h*. To the bed-plate is attached a socket, *i*, through which slides an upright rod, *j*. The rod *j* is held in place by the 55 set-screw *k*, working through the socket-piece *i*. On the top of the rod *j* is a head, *l*, having an adjusting set-screw, *m*, and through the head slides the horizontal slide-rod *n*. This slide-rod *n* is adjustable at any point along its length 60 by the adjusting set-screw *m*. On the outer end of the horizontal slide-rod *n* is a head, *o*, through which works the vertical center *p*. When adjusted the center *p* is held in place by the set-screw *q*. The vertical center *p* has one 65 end pointed and the other concaved or hollowed out, as seen in Fig. 6. At or near the lower end of the vertical center slides a block, *r*, which has a set-screw, *s*, to hold the block at any point on the vertical center. To this 70 block *r* is attached a small clamp, *t*. This clamp is to grasp the outer coil of the hair-spring when the same is being put in and adjusted. The clamp *t* is hung on the horizontal pin *u* and held by the screw *s*. On the vertical center, below the block *r*, is another block, *v*. This block has the sliding rod *w*, which carries two pins, *x x*. These pins serve the purpose of regulator-pins in the watch while the hair-spring is being tested and adjusted by 80 my device. The block *v* is held in its position by the set-screw *y*, Fig. 8. The clamp *t*, for grasping the outer coil of the hair-spring, is operated by the set-screw *z*. On the upright rod *j* is a socket, *a'*, through which passes the 85 horizontal arm *b'*. This arm *b'* has at the outer end a hole or slit, into which is inserted a bristle, *c'*. The arm *b'* is held in its place by a set-screw, *d'*.

The manner of using my device is as follows: 90 Take out the movement from the watch-case, remove the balance-bridge and balance, and then place the movement in the jaws *b* in such a way that the seconds-dial can be clearly seen in the mirror *d*. Then adjust the horizontal 95 slide-rod *n* and the vertical center *p* so that the point of the center *p* will come in the lower jewel-hole of the watch. Now select a hair-spring such as the operator thinks will suit the watch and bring it to time. Then fasten 100 the spring to the balance-staff or balance-arm without pinning it to the collet or removing

any of the inner coils. It may be fastened by means of a spring on the stump, or with wax or any slightly-adhesive substance that will hold it long enough to test the hair-spring. 5 Then set the balance in the watch and bring the vertical center *p* down onto the top pivot with the concave point downward. Care should be exercised to have the balance in an upright position and perfectly free to make its vibrations. Then grasp the outer coil with the clamp *t*, moving at the same time the block *r*, that carries the pin *u*, on which is placed the clamp *t*, in order to put the watch in beat. Then wind up the watch sufficiently to give a 10 good motion to the balance. If, then, it is found by comparison with the chronometer or regulator that the watch loses, grasp it with the clamp *t* in another place farther in on the coil, and again test it. Care must be used not to 15 cut down the hair-spring to too small a diameter. If the watch gains on the first trial, or on the trial of the first hair-spring, then select a weaker spring and test as above described. Bring the regulator-pins *x* of the device as 20 nearly into the same position as those on the watch as is possible. By repeating these tests until the seconds-hand is found to conform to the operator's regulator or standard the hair-spring can be set and adjusted. 25

The bristle *c'* is employed to stop and start 30 the balance as desired.

It should be observed that the hair-spring works between the pins *x x* in the same manner as it does between the regulator-pins of the watch. 35

What I claim as my invention, and desire to secure by Letters Patent of the United States, is—

1. In combination with the plate *a* and mirror *d*, the jaws *b*, the upright rod *j*, horizontal 40 slide-rod *n*, vertical center *p*, and clamp *t*, as herein set forth.

2. In combination with the vertical slide-rod *p*, the block *r*, sliding rod *w*, pins *x x*, and set-screw *y*, as herein set forth. 45

3. In combination with the vertical rod *j*, the horizontal rod *b'*, socket *a'*, set-screw *d'*, and bristle *c'*, all as herein set forth.

In testimony that I claim the foregoing as my own I affix my signature in presence of two 50 witnesses.

CHARLES H. LUCAS.
